UNITED STATES PATENT OFFICE

JAMES G. FROMMEYER, OF CINCINNATI, OHIO

STEPLADDER

Application filed June 13, 1928. Serial No. 285,184.

This invention relates to improvements in stepladders, and is particularly directed to a stepladder of the type incorporating a work platform.

5 It is an object of this invention to provide a stepladder of this type incorporating a work platform of relatively large area in which side rails are provided at the extreme upper end of the ladder at an elevation considerably above the platform, these rails functioning as guard rails and enabling the workman to brace himself thereagainst when standing on the platform.

10 Another object is to provide a pivoted arrangement of the side rails and ladder upright frames as well as an improved mounting of the platform permitting the collapsing or folding of the platform into an extremely flat and compact form.

15 20 Another object is to provide a folding stepladder construction which is staunch and rigid when set up in use, and in which the platform in set-up position functions to brace and steady the stepladder.

25 Still another object is to provide a positive and strong device for sustaining the loaded platform.

Other objects relate to the metal and wood fabrication of the stepladder which with further advantages will be apparent from the description of the accompanying drawings, in which:

30 Figure 1 is a perspective view illustrating the improved stepladder in set-up position.

35 Figure 2 is a fragmentary sectional view taken on line 2—2, Figure 1, detailing the upper portion of the stepladder.

40 Figure 3 is a sectional view taken on line 3—3, Figure 2, further detailing the upper portion of the stepladder.

45 Figure 4 is a side elevation of the upper portion of the stepladder showing it in folded position, showing a pivot reinforcing element in section and further illustrating the forming of the side rails to permit complete folding of the stepladder.

50 Figure 5 is a fragmentary view of the extreme upper end of the stepladder, showing the stepladder in set-up position and detail-

ing the double pivotal connection of the frames thereof.

Figure 6 is a perspective view of one of the U-shaped clips for reinforcing the pivotal connection of the top side rails to the front frame.

Referring to the drawings, a pair of upright stepladder frames, namely front and rear, are indicated respectively at 1 and 2, these frames being pivotally joined at the upper ends thereof. The forward of the frames may be referred to as a step frame, being composed or fabricated of a pair of side pieces 3—3 joined by steps 4. The rear upright 2 is fabricated of a pair of side frames 5—5 joined by a pair of diagonally disposed braces 6—6 and a lower cross piece 7, the upper ends of the side frames of the rear upright being joined by means of a metal cross piece 8.

55 A work platform 9 is pivotally mounted between the frames adjacent the top step thereof. A hinged attachment for the forward end of the platform is provided by means of a pair of pivot brackets 10 secured to the sides of the upright, each having platform attaching portions extending rearwardly and connected to the respective extending forward side flange of the angle iron platform side pieces 11 by means of pins or rivets 12.

60 The rear end of the platform is slidably mounted in the rear frame. A pair of guide rails 13 formed of sheet plate are secured along the respective outer sides of the rear frame and have slots 14 formed longitudinally therein, these slots, by this arrangement, being disposed longitudinally of the rear frame. The slotted portions of the guide rails extend forward from the side pieces 5 or points of attachment, the slotted portions being therefore sufficiently clear thereof for a purpose hereinafter described.

65 70 The slidable connection of the platform to the rear frame is by means of a rod 15 traversing the extending ends of the side flanges 16 of the platform angle iron cross pieces and slidably traversing the slots 14. This pivot rod is a long tie bolt having nuts 17 on the ends thereof for maintaining the same

properly relative to the rails. The body of the platform is constructed of a series of boards extending crosswise between the angle iron side pieces 11 and the ends of the boards set within the angles and riveted thereto. As shown in Figure 5 the platform when in its set-up position is disposed in the same horizontal plane as the top step of the front frame.

10 The lower ends of the guide rails are slit and portions of each turned inwardly below the base end of the slot thus providing flanges 18 disposed in the path of downward swing of the platform rear end and these flanges, 15 as shown in Figure 2, are adapted to serve as rests for the platform, being engaged by the angle iron side pieces 11 thereof. This engagement of the platform with the flanges 18 occurs at just the time that the slide rod 20 15 engages the lower end of the slots 14. As a further support for the platform in its set-up position, a strip of metal 19 is secured to the underside thereof at a central point and extends rearwardly having a down-turned 25 flange 20 providing a sort of hook which engages over a cross rod 21 drawn between the side pieces of the rear frame.

30 The front and rear frames are joined together at the upper ends thereof through a double pivotal connection for a purpose hereinafter described.

35 A pair of side rails 22, one at each side of the stepladder, join the respective adjacent side pieces of the front and back frame each being pivotally connected to the rear frame by means of bolts 23 and to the front frame by means of bolts 24. The previously mentioned cross strap 8 has downturned flanges 25 traversed by the carriage bolts 23, joining 40 the side pieces of the rear frame. The pivotal connection of the side rails to the front frame is reinforced by means of U-shaped clips or brackets 26, one at each pivot point, one of these brackets being detailed in Figure 6. The brackets straddle the top ends 45 of the side pieces 3 as well as the pivoted forward ends of the side rails and are rigidly secured to the rail by means of rivets 27. The bolts 24 traverse the clips or brackets 50 and are drawn between the flanges thereof.

55 As detailed in Figure 5 the forward ends of the side rails 22 are notched out as at 28 to permit pivotal movement of the rails and front frame relative to each other when the ladder is collapsed. As shown in this view the outer upper corner 29 of the side rails engages the underside of the bight of the U-shaped elements providing a positive abutment or stop when the ladder is set up, making an extremely rigid construction. The rear portion of the bight of the U-shaped elements is cut away as at 30 to the necessary depth to provide a clearance for the collapsing pivotal movement of these elements.

60 65 65 By this arrangement of parts it is pro-

vided that the workman may stand upon the horizontally disposed platform and use the side rails 22 and cross piece or rail 8 for bracing himself. The distance from the platform to the rails or extreme top or guard rail of the stepladder is such that the workman is able to steady himself by engaging his knees against these aforementioned side rails or cross piece.

70 75 80 85 90 95 The three point support for the horizontally disposed set-up platform, namely, the engagement of the slide rods at the base of the slots, the engagement of the platform side angle iron elements with the flanges formed on the guide rails, and the engagement of the center strap with the cross rod provides a positive support for the person using the ladder and at the same time insures that the ladder will not fold up or collapse under the weight inasmuch as this is impossible unless the platform is forced upwardly on its hinge from underneath, whereupon the front frame and side rails will move relatively on their pivots and the whole structure will fold up into the form shown in Figure 4.

Having described my invention, I claim:

1. A device of the class described, comprising, a step frame, a support frame, a pair of links pivoted to and spacing the upper ends of said frames, said links disposed one at each side of the joined structure, a platform hinged to one frame adjacent the top thereof, and means for slidably mounting the swinging end of said platform in the other frame for limited downward movement of the platform.

2. A device of the class described, comprising, a front frame formed of side pieces joined by steps, a rear frame formed of side pieces joined by braces, a pair of side rails connected at their ends to the respective front and rear frames, a cross strap joining the upper ends of the rear upright side pieces, a platform hinged to the front frame and slidably at its rear end in said rear frame, abutment means for limiting the downward movement of said platform at horizontal plane, and a connection between the platform and the rear frame for preventing spreading of the frames when the platform is in horizontal plane.

3. A folding stepladder, comprising, a pair of upright frames, links pivotally connected at their ends to the upper ends of the respective frames, said links being disposed one at each side of said connected frames, a cross rail joining the upper ends of the stiles of the rear frame, and a platform hinged to one of said frames, and means for slidably mounting the opposite end of said platform in the other frame.

4. A stepladder construction, comprising, a pair of upright frames, means pivotally connecting the upper ends of said frames, a

platform hinged to one of said frames, a pair of slotted metal guides secured to the respective sides of the other frame, inwardly turned lugs formed integral with the lower ends of said guides, and a slide rod secured in the rear end of said platform and traversing the slots of said guides, said slots terminating relative to said lugs so as to provide, in combination with the lugs, a rest for the platform rear end at horizontal plane.

5. A stepladder construction, comprising, a pair of upright frames, means pivotally connecting said frames at the upper ends thereof, a platform hinged to one of said frames, a pair of slotted guides secured to the respective sides of the other frame, a rod mounted in the outer end of said hinged platform and slidably mounted in said guide rails, downward movement of the platform rear end being limited by engagement of the rod with the lower ends of the slots, a draw rod extending between the sides of the rear frame adjacent the ends of the slots, and an extension formed rearwardly 20 and centrally of said platform engaging said rod and, in combination with the slot ends, supporting the platform in horizontal plane.

25 In witness whereof, I hereunto subscribe my name.

30 JAMES G. FROMMEYER.
